DESIGN FOR A DRAIN COCK

William T. Bentley, Cleveland Heights, Ohio

Application August 20, 1936, Serial No. 64,493

Term of patent 14 years

To all whom it may concern:

Be it known that I, William T. Bentley, a citizen of the United States and resident of Cleveland Heights, in the county of Cuyahoga and State of Ohio, have invented a new, original, and ornamental Design for a Drain Cock, of which the following is a specification, reference being had to the accompanying drawing, forming a part thereof.

In said drawing, Fig. 1 is a plan view of a drain cock showing my new design; Fig. 2 is a side elevational view; and Fig. 3 is a front elevational view.

I claim:

The ornamental design for a drain cock, as shown.

WILLIAM T. BENTLEY.
